UNITED STATES PATENT OFFICE

2,568,714

SOAP HOLDER

Howard Lester Britton, York, Pa.

Application July 20, 1945, Serial No. 606,136

10 Claims. (Cl. 45—28)

1

My herein disclosed invention is a soap cake supporting device and its object is to provide means for suspending a bar of soap in any place or position desired.

A principal object of this invention is to provide means whereby soap may be conserved and kept dry when not being used.

A further object of the invention is to provide means whereby a cake of soap may not escape its user and slide across a floor of linoleum, wood or the like, as often happens when scrubbing the floor which causes additional and uncalled for labor on the part of the user in raising from the knees and chasing after the same, or dropping from a lavatory and sliding under a tub, or the like.

Other features and advantages will become more readily apparent from the following description and the accompanying illustrative drawings in which:

Figure 1 is a sectional elevation of my device.

Figure 2 is an elevational view of the invention showing another application thereof.

Figure 3 is a detail elevational view of a suction cup forming a part of the invention, and

Figure 4 is a detail view of a soap anchor.

In the accompanying drawings as above enumerated and in the following specification, like characters of reference indicate like parts throughout and in which 10, is a view illustrating one application of my invention and 11, illustrates another application thereof. In the form of which 10, is the illustration, there is provided two anchor supporting devices 12 and 13, suitably spaced apart and as both of these supports or brackets are exact counterparts of one another, it will be necessary to describe only the member 12, in detail. This support 12, consists of a rubber or the like frusto-conical suction cup 14, over which is secured a larger frusto-conical cap 15, held thereto with its inside end wall against the small end of cup 14 but spaced at the peripheral conical portion to allow flexing and gripping action of the suction cup 14 by means of a screw 16 having its head anchored in the end wall of cup 14 when molded and projecting therefrom, to the outer end of which is secured a bracket member 17 having a tapered body with a threaded socket in which the projecting end of screw 16 is engaged, having a central projecting shank or arm 18, provided on one side with a series of teeth 19, between any two of which may be held the head portion 20, of the enlargement 21, of an anchor strip or shank 22, which anchor is provided with a longitudinal series of spaced outwardly projecting struck out teeth 23. The member 21, is also provided with inwardly extending tapered teeth 24 and 25 spaced on opposite sides of strip 22. The anchor device 26, is adapted to be projected into a cake of soap 27 at toothed

2

strip or shank 22 and teeth 24 and 25 to prevent displacement as well as twisting or turning of the cake, as clearly indicated in Figure 1 of the drawings, and the member 21, thereof is adapted to be suspended from the projection 18, whereby the cake of soap 27, will be held from contact with any moisture. A cross stop 28, is provided on the reduced end 29, of the member 17 to engage the enlargement 21 when engaged over the notched shank or arm 18, for limiting the movement of said cake of soap. It will be noted that the opening 30, in the member 21, is substantially triangular and the apex 31, engages the member 18, and the edges 32 and 33, engage the side walls of said member 18, whereby swinging motion of the cake of soap is obviated.

It will be noted that the cup 14 projects from cap 15 and may be secured to any flat surface, such as a tile wall 34, at any convenient place over a wash basin to support or suspend the cake 27 from a single supporting device or holder as seen in Figure 2, whereby the soap will always be handy and will not disintegrate through setting in water in a soap dish or upon a wet surface. It will also be noticed that the soap may be suspended from a pair of members such as 12 and 13 as seen in Figure 1, in case it should be desired to secure the said members 12 and 13, upon a horizontal or vertical surface.

My soap anchor is so designed as to be inserted in the soap by the manufacturer when said soap is being moulded into cake form ready for subsequent use. Then too, it gives individuality in selection of more than one kind of soap by using two or more soap holders.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention that which I claim as new and desire to procure by Letters Patent is:

1. A device as described, consisting of a bracket, a soap anchoring member removably connected thereto, said bracket including a rack bar having teeth for adjustable connection with the anchor, means for suspending the bracket, a conical suction cup forming said means, an enclosure member for the cup, a large headed screw the head of which is embedded in the apex of the cup and which connects the enclosure member and bracket to the cup, said anchoring member having a tooth engaging element, and a toothed extension for embedding into a cake of soap.

2. A device as described, consisting of a bracket, a soap anchoring member removably connected thereto, said bracket including a rack bar having teeth for adjustable connection with the anchor, means for suspending the bracket, a conical suction cup forming said means, an enclosure member for the cup, a large headed screw the head of which is embedded in the apex of the cup and which connects the enclosure member and bracket to the cup, and said anchoring member having a tooth engaging element.

3. A device as described, consisting of a bracket, a soap anchoring member removably connected thereto, said bracket including a rack bar having teeth for adjustable connection with the anchor, means for suspending the bracket, a conical suction cup forming said means, an enclosure member for the cup, and a large headed screw the head of which is embedded in the apex of the cup and which connects the enclosure member and bracket to the cup.

4. A device as described consisting of a bracket, a soap anchoring member removably connected thereto, said bracket including a rack bar having teeth for adjustable connection with the anchor, said anchor having a loop for engagement with the teeth of the rack bar, means for suspending the bracket, a conical suction cup forming said means, and an enclosure member of rigid material for the cup and attached to the apex thereof and from which the lip of the cup projects.

5. A soap holder comprising a conical suction cup, a threaded shank anchored at the apex of the cup and projecting therefrom, a conical rigid closure partially covering the cup and mounted on the shank, a bracket threaded on the shank and having a projecting arm provided on one side with a series of teeth, and an anchor adapted to engage and be retained in a bar of soap and provided with a head having a tapered opening with the tapered end thereof of adjustably engaged over the teeth of the arm.

6. A soap holder comprising a bracket, a soap-anchoring member removably connected thereto, said bracket including a body having a central toothed shank for adjustable engagement of the anchor thereover, a conical suction cup for suspending the bracket, a rigid conical enclosure for and spaced over the cup and from which the open end of the cup projects, means for securing the enclosure to the apex portion of the cup at the outside and detachably connecting the body of the bracket thereto against the attaching portion of the enclosure, said anchoring member comprising a toothed strip having an enlargement rigid with one end provided with an outwardly tapered opening to engage over the toothed shank in binding engagement between the teeth thereof, said toothed strip adapted to be embedded in one end of a cake of soap.

7. A soap holder comprising a bracket, a soap-anchoring member removably connected thereto, said bracket including a body having a central toothed shank for adjustable engagement of the anchor thereover, a conical suction cup for suspending the bracket, a rigid conical enclosure for and spaced over the cup and from which the open end of the cup projects, means for securing the enclosure to the apex portion of the cup at the outside and detachably connecting the body of the bracket thereto against the attaching portion of the enclosure, said anchoring member

comprising a toothed strip having an enlargement rigid with one end provided with an outwardly tapered opening to engage over the toothed shank in binding engagement between the teeth thereof, said toothed strip adapted to be embedded in one end of a cake of soap, and a cross stop on the body projecting from diametrically opposite sides thereof to limit the movement of the anchor over the toothed shank and engage the end of the cake of soap for limiting the movement of said cake of soap.

8. A soap holder consisting of a bracket, a soap-anchoring member removably connected thereto, said bracket including a tapered conical body having a central notched shank, a conical suction cup for suspending the bracket, an enclosure member for and spaced over the cup and from which the open end of the cup projects, a screw having an enlarged head anchored in the apex portion of the cup centrally and projecting therefrom at the back, said enclosure member having a thickened apex wall with a bore receiving said screw therethrough and projecting therefrom, said body having a threaded socket for engagement by the screw to detachably secure the body to the enclosure and against the apex portion thereof, said anchoring member having a toothed extension for embedment in a cake of soap and means on opposite sides thereof for engaging in the end of the cake of soap to prevent turning or twisting of the cake.

9. A soap holder comprising a bracket adapted for attachment to a supporting surface and having a projecting toothed bar rigid therewith, and a strip member adapted to be anchored at one end in one end of a cake of soap and provided on its other end with an integral head having an opening which is adapted to removably receive the toothed bar and which tapers toward the free end of the head so that movement of said strip member in opposite directions transversely of the toothed bar will respectively cause engagement of the head with and disengagement of the same from the teeth of said bar.

10. The construction defined in claim 9, in combination with a stop member carried by and projecting laterally from the toothed bar and adapted to abut against the adjacent end of a cake of soap in which the strip member is anchored, when the head of said strip member is engaged with the teeth of said tooth bar, to hold the cake of soap in spaced relation to the supporting surface.

HOWARD LESTER BRITTON.
